Application December 10, 1943, Serial No. 513,791

13 Claims. (Cl. 237—10)

1

This invention relates to heating systems and more particularly to the control of temperature in vapor heating systems.

The invention provides a novel vapor heating system in which the temperature of a substance heated by a condensable vapor is automatically controlled by the use of a regulated quantity of non-condensable vapor.

The invention will be understood from the following description when considered in connection with the accompanying drawings forming a part thereof and in which:

Fig. 1 is a diagrammatic view of a closed vapor heating system of the present invention having a single heat user;

Fig. 2 is a view similar to Fig. 1 but showing a closed vapor heating system having a plurality of heat users;

Fig. 3 is a sectional view showing one manner of connecting a heat user into the heating system, and

Fig. 4 is a sectional view of a pressure compensating valve used in the heating system of the present invention.

Like characters of reference refer to like parts throughout the views.

Referring to the drawings, the reference numeral 10 designates the setting of a vapor generator for generating a condensable vapor from a high boiling point liquid such as diphenyl, diphenyl oxide or an equivalent high boiling point liquid. The generator has an upper drum 11 and a lower drum 12 connected by a main bank of vapor generating tubes 13. A combustion chamber 14 fired by burner 15 is positioned at one side of the tube bank, the products of combustion from which are directed over the tube bank by baffles and thereafter pass into a flue at the opposite side of the bank 13. The walls of the chamber are lined by tubes 16 which are connected into the circulatory system of the generator. It will be understood that other types of vapor generators may be used if so desired. The drum 11 of the vapor generator is connected, as shown in Figs. 1 and 2, to the top of a heat user 17 by means of a condensable vapor conduit 18. The flow of vapor through the conduit 18 is controlled adjacent the drum 11 by a valve 19 and adjacent the user 17 by means of the valve 20.

The heat user 17, as shown, is in the form of a container and has a chamber 21 adapted to receive a substance to be heated. The wall 22 of the heat user 17 is surrounded by a vapor jacket 23 which jacket is in communication with the condensable vapor conduit 18. The inner surface of the wall 22 of user 17 constitutes the heating surface by means of which the substance in the chamber 21 is heated. A vapor outlet connection 24 is in communication with the

2

jacket 23 at the bottom of the user 17. The connection 24 is in communication with the bottom of the drum 12 of the vapor generator through a return conduit 25 through which condensate from the jacket is returned to the vapor generator. If the user 17 is positioned at an elevation sufficiently high above the vapor generator, gravity may be depended upon for the return of condensation to the vapor generator. Should the elevation of the user not be sufficiently high, a return pump 26 is used. The suction side of the pump 26 is connected to the conduit 25 by means of a pipe 27, while the discharge side of the pump is connected to the conduit 25 by means of conduit 28. The pump 26 may be connected into or disconnected from the conduit 25 by means of a valve 29 in the conduit 25 at a point between the point of connection of the conduits 27 and 28 to the conduit 25 and also by means of a valve 30 in the conduit 27.

The temperature to which the substance in the chamber 21 of the user 17 is heated is regulated by the introduction of non-condensable vapor into and the withdrawal of non-condensable vapor from the jacket 23 of the user 17. The greater the amount of non-condensable vapor in the jacket 23 the lesser the degree to which the inner surface of the wall 22 is heated and conversely, the lesser the amount of non-condensable vapor in the jacket 23 the higher the degree to which the inner surface of the wall 22 is heated. In order to introduce or withdraw non-condensable vapor from the jacket 23 and thereby control the temperature to which the substance in the chamber 21 of the user 17 is heated, a conduit 31 is connected at one end to the discharge outlet 24 at a point intermediate the point at which the outlet connection 24 is connected to the jacket 23 and the point at which the conduit 25 is connected to the outlet connection. The opposite end of conduit 31 is connected to a conduit 32 which is in communication at one end with a suction chamber 33. The conduit 32 is controlled at a point between the suction chamber and the point at which conduit 31 is connected thereto by a solenoid valve 34 which valve is adjusted to be opened against the tension of a spring 35 when the solenoid 36 is energized and to be closed by the tension of the spring when the solenoid is de-energized. The suction chamber 33 is in communication with the suction side of a pump 37 through a conduit 38. The pump 37 is preferably of the centrifugal hydraulic type which is sealed with a liquid similar to that used in the vapor generator and is adapted to compress non-condensable vapors received from the user 17 through the conduit 31, suction chamber 33 and conduit 38 and pass the same through a discharge conduit 39 into the bottom of a container 40 having a con-

densing coil 40' through which a cool fluid flows. A return conduit 41 controlled by a regulator valve 42 is connected at one end to the bottom of the container 40 and at the other end to the conduit 38 so that sufficient sealing liquid will be returned to the compressor 37 to assure continuous operation thereof. Conduit 32 also is in communication with the top of the receiver 40 and receives non-condensable vapors from said receiver. The conduit 32 is controlled by a solenoid valve 43 at a point between the connection of said conduit to the receiver and the point of connection of the conduit 31 to the conduit 32. The valve 43 is adapted to be opened against the tension of the spring 44 when the solenoid 45 is energized and to be closed by the tension of said spring when the solenoid is de-energized. The container 40 is provided with a float valve 46 which prevents the liquid in the container 40 from rising above a predetermined level. The valve 46 controls an outlet which is in communication with the condensate return conduit 25 through a pipe 47 so that when the liquid in the container 40 rises above a predetermined level, the valve 46 will be opened and the excess liquid will flow through the line 47 into the condensate return line 25 thence into the vapor generator.

In order to regulate the temperature to which the substance in the chamber 21 of the heat user 17 is heated, a thermostatic control which governs the flow of non-condensable vapors into the jacket 23, and also governs the withdrawal of non-condensable vapor from the jacket by controlling the operation of the valves 34 and 43, is provided. The thermostatic control comprises a bulb 48 inserted in the chamber 21 in such a position that it will be contacted by a substance in said chamber. The bulb 48 is connected by capillary tubing 49 to a Bourdon tube 50 which tube is responsive to any rise or fall of temperature in the chamber 21. A movable contact arm 51 is connected to the Bourdon tube 50 and is actuated into and out of contact with adjacently disposed fixed contacts 54 and 55 by said tube. The contact arm 51 is in electrical connection through lines 52 and 53 with pole A of an electrical source. The fixed contacts 54 and 55 are positioned at opposite sides of the arm 51 and normally are in spaced relationship thereto. The contacts are adjustable so that the space between either of them and the movable contact may be varied as desired. Fixed contact 55 is in electrical connection with the coil 56 of a solenoid switch 57 through a line 58. Coil 56 is electrically connected through lines 59 and 60 to the pole B of the electrical source. One of the fixed contacts 61 of the solenoid switch 57 is connected to the line 53 by the lines 62 and 63 while the other fixed contact 64 is connected to the solenoid 36 of the solenoid valve 34 by means of the line 65. The solenoid 36 is also electrically connected to the line 60 by means of the line 66.

The fixed contact 54 is connected to the adjustable fixed contact 61 of a fluid pressure responsive switch 68 through a line 69. The fluid pressure responsive switch 68 comprises a movable contact arm 70 adapted to be moved into and out of engagement with fixed contacts 67 and 71 by the action of bellows 72 and 73. The operation of the switch 68 will hereinafter be fully set forth. Normally, however, the contact arm 70 will be in engagement with the fixed contacts 67 and 71. The fixed contact 71 of the switch 68 is connected to a coil 74 of a solenoid switch 75 by the line 76. The coil 74 is also connected to the line 60 through the line 77. The fixed contact 78 of the

switch 75 is connected to the line 53 through the line 63 while the other fixed contact 79 is in electrical connection with the coil 45 of the solenoid valve 43 through the line 80. The coil 45 is also connected to the line 60 through the lines 81 and 66.

In order that an amount of non-condensable vapor in excess of the capacity of jacket 23 will not be delivered to the jacket and flow back into the 10 vapor generator through the conduit 18, an automatic control is provided which control is adapted to actuate the switch 68 and break an electrical circuit to the valve 43 so that the valve will close and prevent further flow of non-condensable 15 vapor from the container 40 to the jacket when the capacity thereof is reached. This control comprises a pressure drop or tell-tale device 82 which, as shown in Figs. 1 and 2, is connected to the heat user 17 adjacent the top and to the side thereof opposite that to which the condensable vapor conduit 18 is connected. The tell-tale device 82 has a chamber 83 therein which is in communication through a port 84 with the jacket 23. An inlet orifice plate 85 is positioned in the chamber 83 adjacent port 84, the inlet orifice plate 85 having an orifice therein of a lesser diameter than that of the port 84. Adjacent the opposite end of the chamber 83 of the device 82, is an outlet orifice plate 86 similar to the plate 85. The body 30 of the device 82 is provided on the outside thereof with condensing means which extends between the two orifice plates and, as shown, comprise a plurality of radiating fins 87 each of which extends circumferentially of the device in spaced 35 relationship with one another. Device 82 is connected at the end thereof adjacent the orifice plate 86 to the suction chamber 33 by means of the conduit 88. Vapors are drawn from the jacket 23 through the port 84, aperture plate 85, chamber 83 and aperture plate 86, conduit 88, suction 40 chamber 33 and conduit 38 by the pump 37. During normal operation of the system, a small amount of the condensable vapor in the jacket 23 is drawn through the tell-tale device. A large 45 portion of this vapor is condensed in the chamber 83 thereof, the condensate passing into the jacket 23 through the loop seal 89. Consequently, only a small portion of the condensable vapors will remain to flow through the orifice plate 86 which 50 results in a small pressure difference between the upstream and downstream sides of the plate 86. When the jacket 23 becomes filled with non-condensable vapor and the same, together with a small amount of condensable vapor, is drawn 55 through the tell-tale device, since none of the non-condensable vapor will be condensed in the chamber 83, there will be a greater pressure drop between the upstream and downstream sides of the plate 86 than when condensable vapor alone is 60 drawn through the device. The pressure responsive switch 68 is adapted to be actuated by the pressure drop across the plate 86, the bellows 73 of said switch being in communication with the device 82 on the downstream side of the plate 86 through the tube 90 while the bellows 72 is in communication with the chamber 83 on the upstream 65 side of the orifice plate 86 through the tube 91. Increased pressure in the chamber 83 on the upstream side of the plate 86 when non-condensable 70 vapor is drawn through the tell-tale device causes the bellows 72 of the switch 68 to expand moving the arm 70 to the left of Figs. 1 and 2, against the smaller amount of pressure in the bellows 73, and out of contact with the fixed contacts 67 and 75 75 71 breaking the circuit to the valve 43 causing

the same to close and thereby prevent further non-condensable vapor from passing into the jacket 23, as will hereinafter be fully described.

A differential pressure control valve 92, which is shown in detail in Fig. 4, is positioned in the line 88 and operates to maintain a constant difference in pressure between the section of the line 88 extending from the device 82 to the valve 92 and the pressure in the jacket 23. The valve 92 comprises oppositely disposed bellows 93 and 94, the bellows 93 engaging one end of a valve stem 95 having a valve 96 attached thereto which valve is adapted to be seated on seats 97 while the bellows 94 is adapted to engage the opposite end of the valve stem. The bellows 93 is in communication with the jacket 23 through the conduit 95 while the bellows 94 is in communication with the line 88 at a point between the valve 92 and the outlet end of the device 82 through a conduit 96'. An adjustment is provided for compensating for the difference in pressure between the pressure within the bellows 93 and the pressure within the bellows 94 so that the valve 96 will be moved toward its open position when the pressure in the bellows 94 increases beyond a predetermined amount in relation to the pressure in the bellows 93 and will be moved toward its closed position when the pressure in the bellows 93 increases beyond a predetermined amount in relation to the pressure in the bellows 94. This adjustment comprises an adjusting nut 122, which cooperates with threads on the valve stem 95, and a spring 123 which acts upon the nut and a fixed plate 124 having an aperture of greater diameter than the valve stem and through which the valve stem extends. Normally, as determined by adjustment of the adjusting nut 122, the valve 96 is unseated sufficiently to permit vapor to flow through the line 88. Should the pressure in the jacket 23 increase with respect to the balancing pressure in the tubes 86 and 96', the pressure in the bellows 93 will increase relatively to that in the bellows 94 which causes the valve 96 to move toward a closed position thereby decreasing or stopping the flow of vapor through the line 88 which causes pressure to build up in the line 88 between the valve 92 and the outlet of the device 82. The pressure will increase in the lines 88, 96' and bellows 94 until the pressure therein counterbalances the pressure in the bellows 93. As the pressure in the bellows 94 is increased, the valve 96 is returned toward its normal open position. Should the pressure in the line 88 between the valve 92 and the device 82 increase above that in the line 95 the increased pressure is conveyed through the line 96' to the bellows 94 which causes the bellows to expand. Since the pressure in the bellows 94 will increase relatively to the pressure in the bellows 93, the valve stem will be moved in a direction which causes the valve 96 to be moved away from the seat 97 thereby permitting a greater flow of vapor through the line 88 and decreases the pressure therein. As the pressure in the lines 88 and 96' decreases, the pressure in the bellows 94 decreases which causes the valve 96 to move toward its closed position. When the pressure in the bellows 93 and the pressure in the bellows 94 counterbalance the valve 96 will be in its normal position.

It is necessary to insure a sufficient amount of non-condensable gases always being available in the container 40. To insure an adequate supply of said gases, a non-condensable vapor container 100 is in communication with the container 40 through a conduit 101 which is connected to said

container above the normal level of liquid therein. The flow of gases from the container 100 into the container 40 is controlled by the normally closed solenoid valve 102 in the conduit 101. To control the opening and closing of the valve 102, a differential pressure control valve 103 is used which valve comprises opposed bellows 104 and 105 and a movable contact arm 106 positioned intermediate the bellows. Bellows 105 is in communication with the upper part of the container 40 through a conduit 107 while bellows 103 is in communication with the condensable vapor line 18 through the conduit 108. The contact arm 106 is normally out of engagement with the fixed contacts 109 and 110. The fixed contact 109 is connected to the coil 111 of the solenoid switch 112 through the line 113. The coil 111 is also connected to line 53 through line 114. Fixed contact 110 of the switch 103 is connected to the line 60 through the line 115. The fixed contact 116 of the solenoid switch 112 is connected to the line 53 through the line 117 while the other fixed contact 118 is in electrical connection with the coil 119 of the solenoid valve 102 through line 120, the coil 119 being connected to the line 60 through the line 121.

In operation, condensable vapor is generated in the vapor generator by passage of the gases of combustion from the burner 15 in heat exchange relationship with the bank of vapor generating tubes 13 and the tubes 16. Vapor passes from the drum 11 into the jacket 23 of the heat user 17 through the open valve 19, condensable vapor conduit 18, and open valve 20 to thereby heat the substance in the chamber 21. When the substance in the chamber 21 is heated above a predetermined temperature, as determined by the thermostatic bulb 48, the Bourdon tube 50 is actuated by heat transmitted thereto through the capillary tubing 49 to move the contact arm 51 into engagement with the fixed contact 54. Electric current will then flow from the pole A through lines 53 and 52 into contact arm 51, thence through the fixed contact 54, line 69, into fixed contact 67, movable contact 70, and fixed contact 71 of the switch 68 and then into the coil 74 of the switch 75 through the line 76. Coil 74 will thereby become energized since the coil also is in electrical connection with the pole B through the lines 77 and 60. Energizing of the coil 74 will cause the movable contact of the switch 75 to be brought into engagement with the fixed contacts 78 and 79 of said switch which will permit electric current to flow from the line 53 through the line 63, fixed contact 78, movable contact 75' and fixed contact 79 of the switch 75, thence through the line 80 into the coil 45 of the solenoid valve 43 which energizes the same because said coil is in connection also with the line 60 through the lines 81 and 66. Energizing of the coil 45 causes the valve 43 to be opened against the tension of the spring 44 permitting non-condensable vapor to flow from the container 40 through the conduit 32 into the conduit 31 thence, into the jacket 23 of the heat user 17 through conduit 31 and outlet connection 24. The non-condensable vapor thus flowing into the jacket 23 tends to blanket the wall 22 of the heat user 17 against contact with the condensable vapor flowing into the jacket through the conduit 18. The degree to which the wall 22 is heated is thereby reduced which in turn reduces the degree to which the substance in the chamber 21 is heated. The greater the amount of non-condensable vapor in the jacket 23 the lesser the degree to which the substance in the chamber 21 is heated. The ther-

mostatic bulb 48 causes the Bourdon tube 50 to be actuated to break the connection between the movable contact 51 and the fixed contact 54 when the temperature to which the substance in the chamber 21 of the heat user 17 is heated is decreased to a predetermined degree. The coil 74 of the solenoid switch 75 is deenergized, when the contacts 51 and 54 are disengaged, permitting the spring in said switch to move the movable contact out of engagement with the fixed contacts 78 and 79. Disengagement of the movable arm of the switch 75 from the contacts 78 and 79 breaks the electrical circuit to the coil 45 of the solenoid valve 43 causing said valve to be closed by the action of the spring 44. Flow of non-condensable vapor from the container 40 through the conduits 32 and 31 and into the jacket 23 of the user is thereby stopped. Should the degree to which the substance in the chamber 21 of the user 17 is heated decrease below a predetermined degree, the thermostatic bulb 48 will cause the Bourdon tube 50 to move the movable contact 51 into engagement with the fixed contact 55 which permits current to flow from the pole A through lines 53 and 52, movable contact 51, fixed contact 55 and line 58 into the coil 56 of the solenoid switch 57 thereby energizing the coil because said coil is connected to the pole B through the lines 59 and 60. Energizing of the coil 56 causes the movable arm of the switch 57 to move into engagement with the fixed contacts 61 and 64 thereby closing said switch. Current will then flow from the line 53 into the lines 63 and 62, into the fixed contact 61, through the movable arm of the switch 57 into the fixed contact 64, through the line 65 and into the coil 36 of the solenoid valve 34 in conduit 32. Since the coil 36 is connected to the line 60 through the line 66, it becomes energized, thereby opening the solenoid valve 34 against the tension of the spring 35. Opening of the solenoid valve 34, permits non-condensable vapor to be withdrawn from the jacket 23 by the pump 37, which is operated continuously, the non-condensable vapor being withdrawn through conduits 31 and 32, suction box 33 and conduit 38 by said pump and thence discharged into the container 40 through the conduit 39. Any condensable vapor withdrawn from the jacket 23 with the non-condensable vapor is discharged into the container 40 and is condensed by cooling coil 40'. When the condensate rises above a predetermined level in the receiver, the valve 46 is opened permitting the excess condensate to flow through the conduit 47 into the return conduit 25 and thence into the drum 12 of the vapor generator. Condensate formed from the condensable vapor in the jacket 23 flows through the conduit 25 into the drum 12 of the vapor generator as hereinbefore set forth.

Withdrawal of non-condensable vapor from the jacket 23 reduces the amount of non-condensable vapor in the jacket, decreasing the area of the wall 22 blanketed by the non-condensable vapor and providing a greater space in the jacket for condensable vapor. The greater the amount of condensable vapor in the jacket 23, the greater the area of the wall 22 which will be contacted by the condensable vapor and the higher the temperature to which the wall 22 and the substance in the chamber 21 will be heated. The thermostatic bulb 48 will cause the movable contact arm 51 of the Bourdon tube 50 to disengage the fixed contact 55 when the temperature of the substance in the chamber 21 is raised above a predetermined temperature.

Under normal operating conditions, the jacket 23 is substantially entirely filled with condensable vapors. A small amount of these vapors will flow into the tell-tale device 82 through the port 84 and orifice plate 85 at a continuous rate. A large portion of such vapors passing into the device 82 will be condensed in the chamber 83 of the device between the orifice plates 85 and 86, the condensate passing from the chamber 83 through the loop seal 89 into the jacket 23. A small portion of the condensable vapors will remain uncondensed and flow through orifice plate 86 thence out of the tell-tale device and into the conduit 88. This results in a small pressure difference between the upstream and downstream sides of the orifice plate 86. Under such conditions, the pressure responsive switch 68 is closed, the movable arm 70 thereof being in contact with the fixed contacts 67 and 71. Also, the valve 92 is in its normal open position, that is, the valve 96 is positioned off the seat 97 sufficiently to permit a normal amount of condensable vapor to pass through said valve. Should the movable contact 51 of Bourdon tube 50 remain in engagement with the fixed contact 54 after the jacket 23 is filled with non-condensable vapor, the vapor will continue to flow into said jacket thereby providing an excess of non-condensable vapor which will flow through the port 84, orifice plate 85 and into the chamber 83 of the tell-tale device 82. The amount of condensable vapor passing into the chamber 83 will decrease and the amount of non-condensable vapor will increase so long as contacts 51 and 54 remain in engagement. Since none of the non-condensable vapor passing through the orifice 85 will be condensed in the chamber 83 the volume of vapors passing through the orifice plate 86 into the line 88 will increase. This will cause a greater pressure drop across the orifice plate 86 than would be the case if only condensable vapor was passing from the jacket into the tell-tale device. The pressure on the upstream side of the plate is, therefore, increased. Increased pressure on the upstream side of the orifice plate 86 will cause the pressure in the tube 91 to be increased over that in the tube 90. The increased pressure in the tube 91 will increase the pressure in the bellows 72 over the pressure in the bellows 73 causing the bellows 72 to expand and thereby move the arm 70 to the left of Figs. 1 and 2 and out of engagement with the contacts 67 and 71. Disengagement of the movable contact 70 from the fixed contacts 67 and 71 causes the coil 74 of the solenoid switch 75 to become de-energized causing the movable contact of the switch to move out of engagement with the fixed contacts 78 and 79 thereby breaking the electrical circuit to the coil 45 of the solenoid valve 43, causing said valve to be closed by action of the spring 44. Closing of the valve 43 prevents further flow of non-condensable vapor from the container 40 to the jacket 23 of the user 17.

When the amount of non-condensable vapor in the container 40 falls below the desired quantity, the pressure within the container decreases which in turn causes the pressure in the conduit 107 and bellows 105 of the switch 103 to become lower. Lower pressure in the bellows 105 will cause the higher pressure in the bellows 106 to move the contact arm 106 into engagement with fixed contacts 109 and 110 of the switch 103 closing said switch. Closing of the switch 103 permits electric current to flow from the lines 53 and 114 into the coil 111 of the switch 112 and from the lines 60 and 115 through the contacts 110, 106, 109

and line 113 into the coil 111 thereby energizing said coil. Energizing of the coil 111 closes the switch 112 by moving the movable contact of said switch into engagement with the fixed contacts 116 and 118. Current will then flow into coil 119 through the lines 53 and 117, switch 112 and line 120, and also through lines 60 and 121 thereby energizing said coil and opening the valve 102 against spring tension. Non-condensable vapor from the non-condensable vapor container 100 then flows into the receiver 40 through the conduit 101. When a sufficient amount of non-condensable vapor is introduced into the container 40, the pressure in said container, tube 107 and the bellows 105 will be slightly greater than that in the bellows 104 and sufficient to move the movable contact 106 of the switch 103 out of engagement with the fixed contacts 109 and 110 thereby breaking the electrical circuit to the coil 111 of the switch 112 causing the switch to become opened. Opening of the switch 112, breaks the electric circuit to the coil 119 of the valve 102, de-energizing the coil 119. This causes the valve 102 to be closed by the tension of the spring thereof preventing further flow of non-condensable vapor from the non-condensable container 100 into the container 40.

A heating system similar to that shown in Fig. 1 is illustrated in Fig. 2. The system of Fig. 2, however, has more than one heat user 17 the heating of each of which is controlled independently of the other by apparatus similar to that in the form of the invention shown in Fig. 1. The condensable vapor conduit 18 is extended to communicate with the packet 23' of a second heat user 17' while the condensate return conduit 25 is in communication with the outlet connection 24' of the heat user 17' through the conduit 25'. The suction conduit 38 is extended to communicate with the tell-tale device 82' on the user 17'. Non-condensable vapor is introduced into the jacket 23' of the user 17' through the conduit 32' and the conduit 31'. The conduit 32' is connected at one end to the conduit 32 at a point between the container 40 and the valve 43 of the control apparatus for the user 17 and is connected at the opposite end to the suction line 38. Flow of non-condensable vapor into the packet 23' of user 17' is controlled by the valve 43' in the conduit 32' while flow of non-condensable vapor from the jacket 23' into the container 40 is controlled by the valve 34' in the conduit 32'. The flow of the non-condensable vapor is controlled by said valves in the same manner as in the form of the invention shown in Fig. 1. With the arrangement of apparatus shown in Fig. 2, both of the heat users 17 and 17' are under constant vapor pressure from the vapor generator through the line 18. The heat absorbing capacity of the users 17 and 17' may be varied independently of one another by separately controlling the amount of non-condensable vapor introduced into each without varying the pressure. The pressure is, therefore, maintained constant in a plurality of heat users while the heat absorbing capacity of any user may be varied independently of other heat users.

The tell-tale device 82 in the form of the invention shown in Fig. 3 is connected to the vapor outlet connection 24 at the bottom of the heat user 17. Conduit 31, through which non-condensable vapor is introduced into and withdrawn from the jacket 23 of the heat user 17, is connected to the top of the user 17 while the conduit 18 through which condensable vapor enters the jacket 23 is connected to the connection 24. The

tell-tale device is in communication with the connection 24 at a point between the bottom of the jacket 23 and the point of connection of the conduit 18. After the jacket 23 becomes filled with 5 non-condensable vapor and the flow of vapor to said jacket continues, the excess non-condensable vapor flows through said tell-tale device causing the same to operate the apparatus controlling the flow of non-condensable vapor to the jacket in the same manner as in the form of invention shown in Figs. 1 and 2.

The term "non-condensable vapor" as used in the specification and the term "non-condensable gas" as used in the claims includes a vapor or gas which will not condense in the heat user of the present invention.

Since variations may be made in the form of the invention herein disclosed, it will be understood that the invention is not to be limited excepting by the scope of the appended claims.

What is claimed is:

1. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, means through which non-condensable gas is supplied to said space, a solenoid valve for controlling the flow of non-condensable gas to said space and adapted to be closed when the electrical circuit to the solenoid is open to prevent the flow of non-condensable gas to said space, non-condensable gas withdrawing means, an outlet conduit in communication with the vessel space and said gas withdrawing means, another solenoid valve, said other valve being associated with the outlet conduit and adapted to be closed when the electrical circuit to the solenoid thereof is open to prevent withdrawal of gas from said space, an electrical switch comprising spaced fixed contacts, one of said contacts being in circuit 25 with said first-mentioned solenoid valve and another of said contacts being in electrical circuit with said other solenoid valve, a movable contact cooperating with said fixed contacts, and temperature responsive means for actuating the movable contact, said means being responsive to the temperature of said substance and adapted to move the movable contact into engagement with said one of the fixed contacts and close an electrical circuit to the first-mentioned solenoid valve to thereby open the valve and permit the flow of non-condensable gas to the vessel space when the temperature of said substance rises above a predetermined degree and to move the movable contact into engagement with said other fixed contact and close the electrical circuit to said other solenoid valve to thereby open the valve and permit gas to be withdrawn from said space when the temperature of the substance falls below a predetermined degree.
2. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, means through which non-condensable gas is supplied to said space, non-condensable gas flow controlling means for con-

11

trolling the flow of non-condensable gas to said space, non-condensable gas withdrawing means in communication with the space, non-condensable gas withdrawal controlling means for controlling the withdrawal of gas from the space, temperature responsive means associated with said vessel for controlling the actuation of the non-condensable gas flow controlling means and the gas withdrawal controlling means to regulate the flow of non-condensable gas to and the withdrawal of non-condensable gas from the vessel and thereby regulate the temperature to which the substance is heated, and non-condensable gas cut-off means associated with the vapor space and the non-condensable gas flow controlling means to control the non-condensable gas flow controlling means so that the flow of non-condensable gas to the jacket will be cut off when a predetermined amount of non-condensable gas is admitted to said jacket.

3. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, means through which non-condensable gas is supplied to said space, means for conducting non-condensable gas to said vessel vapor space, electrically operated means for controlling the flow of non-condensable gas to the vessel, non-condensable gas withdrawing means in communication with the vapor containing portion of the vessel, other electrically operated controlling means for controlling the withdrawal of non-condensable gas from the vessel, an electrical switch in circuit with the non-condensable gas withdrawal means and with the gas flow controlling means, temperature responsive means associated with the vessel and with said switch and adapted to actuate the switch and thereby control said electrically operated and said other electrically operated means to control the non-condensable gas withdrawal controlling means and the gas flow controlling means, non-condensable gas cut-off means associated with the vessel space at a predetermined level therein and through which gas flows to the gas withdrawing means from said space, a pressure drop device in the path of flow of gas flowing from said space to the gas withdrawing means through said cut-off device, a second electrical switch in circuit with the non-condensable gas flow controlling means, and differential pressure responsive means in communication with the path of flow of said gas from the space to the gas withdrawing means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

4. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, means through which non-

12

condensable gas is supplied to said space, means for conducting non-condensable gas to said vessel vapor space, electrically operated means for controlling the flow of non-condensable gas to the vessel, non-condensable gas withdrawing means in communication with the vapor containing portion of the vessel, other electrically operated controlling means for controlling the withdrawal of said gas from the vessel, an electrical switch in circuit with the non-condensable gas withdrawal means and with the said gas flow controlling means, temperature responsive means associated with the vessel and with said switch and adapted to actuate the switch and thereby control said electrically operated and said other electrically operated means to control the non-condensable gas withdrawal controlling means and the gas flow controlling means, non-condensable gas cut-off means associated with the vessel space at a predetermined level therein and through which gas flows to the gas withdrawing means from said space, a control valve in said path of flow between the gas withdrawing means and the cut-off means, actuating means for the control valve comprising pressure responsive members, one of said members being in communication with and responsive to the pressure in the vessel vapor space and another of said members being in communication with and responsive to the pressure in said path of flow between the control valve and the cut-off means, said one member acting to move the valve toward its closed position when the pressure therein is relatively greater than in the other member, the other member acting to move the valve toward its open position as the pressure therein increases relatively to the pressure in said one member, a second electrical switch in circuit with the non-condensable gas flow controlling means, and differential pressure responsive means in communication with the path of flow of said gas from the space to the gas withdrawing means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

5. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, a container, conduit means for conducting non-condensable gas from said source to the container, electrically actuated valve means for controlling the flow of non-condensable gas through the conduit means, a switch for controlling the flow of electrical current to said electrically actuated valve, pressure responsive means associated with said switch, said pressure responsive means comprising a member in communication with and responsive to the pressure in the means for conducting condensable vapor and another member in communication with and responsive to the pressure in the container, said one member being adapted to actuate the switch so as to close the electrical circuit to the valve means and cause the same to open when the pressure in said one member is relatively greater

than in said other member, the other member being adapted to actuate the switch so as to open the circuit to the valve means and permit the same to return to its normally closed position when the pressure in said other member is relatively greater than in said one member, means through which non-condensable gas is supplied to said space, means for withdrawing non-condensable gas from the space, and means for regulating the amount of condensable vapor used in said space by controlling the amount of non-condensable gas supplied to and withdrawn from said space to thereby control the temperature to which the substance in the vessel is heated.

6. The combination of a vessel having a wall formed to provide a space adapted to contain a substance, a jacket in spaced relationship to said wall to provide a vapor space between the jacket and the wall, means for generating a condensable vapor heating medium, conduit means in communication with the upper part of the vessel vapor space and with the condensable vapor generating means, a non-condensable gas source, a conduit for conducting non-condensable gas from said source to the lower part of the vessel vapor space, electrically operated means for controlling the flow of non-condensable gas to the vessel, non-condensable gas withdrawing means in communication with the vapor containing portion of the vessel, other electrically operated controlling means for controlling the withdrawal of said gas from the vessel, an electrical switch in circuit with the non-condensable gas withdrawal means and with said gas flow controlling means, temperature responsive means associated with the vessel and with said switch and adapted to actuate the switch and thereby control said electrically operated and said other electrically operated means to control the non-condensable gas withdrawal controlling means and the gas flow controlling means, non-condensable gas cut-off means associated with the upper part of the vessel vapor space at a predetermined level therein and through which gas flows to the vapor withdrawing means from said space, a pressure drop device in the path of flow of gas flowing from said space to the gas withdrawing means through said cut-off device, a second electrical switch in circuit with the non-condensable gas flow controlling means, and differential pressure responsive means in communication with the path of flow of said gas from the space to said gas withdrawing means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

7. The combination of a vessel having a wall formed to provide a space adapted to contain a substance, a jacket in spaced relationship to said wall to provide a vapor space between the jacket and the wall, means for generating a condensable vapor heating medium, conduit means in communication with the lower part of the vessel vapor space and with the condensable vapor generating means, a non-condensable gas source, a conduit for conducting non-condensable gas from said source to the upper part of the vessel vapor space, electrically operated means for controlling the flow of non-condensable gas to the vessel, non-condensable gas withdrawing means in communication with the vapor contain-

ing portion of the vessel, other electrically operated controlling means for controlling the withdrawal of gas from the vessel, an electrical switch in circuit with the non-condensable gas withdrawal means and with the gas flow controlling means, temperature responsive means associated with the vessel and with said switch and adapted to actuate the switch and thereby control said electrically operated and said other electrically operated means to control the non-condensable gas withdrawal controlling means and the gas flow controlling means, non-condensable gas cut-off means associated with the lower part of the vessel vapor space at a predetermined level therein and through which said gas flows to the vapor withdrawing means from said space, a pressure drop device in the path of flow of gas flowing from said space to the gas withdrawing means through said cut-off device, a second electrical switch in circuit with the non-condensable gas flow controlling means, and differential pressure responsive means in communication with the path of flow of said gas from the space to the gas withdrawing means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

8. The combination of a plurality of vessels each having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in each vessel, a non-condensable gas source, means through which non-condensable gas is supplied to the vapor space of each vessel, means for withdrawing non-condensable gas from the vapor space of each vessel, electrically operated means associated with each vessel for controlling the flow of non-condensable gas to the vessel, gas withdrawing means, an outlet conduit in communication with the vapor space of each vessel and the gas withdrawing means, other electrically operated controlling means associated with the outlet conduit of each vessel for controlling the withdrawal of gas from the vessel, an electrical switch associated with each vessel and in circuit with the non-condensable gas withdrawal means and with the gas flow controlling means, temperature responsive means associated with each vessel and with said switch and adapted to actuate the switch and thereby control said electrically operated and said other electrically operated means to control the non-condensable gas withdrawal controlling means and said gas flow controlling means, non-condensable gas cut-off means associated with each vessel space at a predetermined level therein and through which gas flows to said gas withdrawing means from said space, a pressure drop device in the path of flow of gas flowing from each space to said gas withdrawing means through said cut-off device, a second electrical switch associated with each vessel and in circuit with the non-condensable gas flow controlling means, and differential pressure responsive means in communication with the path of flow of said gas from the space of each vessel to the gas withdrawing

means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

9. The combination of a vessel having a wall formed to provide a space adapted to contain a substance, a jacket in spaced relationship to said wall to provide a vapor space between the jacket and the wall, means for generating a condensable vapor heating medium, means through which the condensable vapor is supplied to the space to heat the wall and substance in said vessel, a non-condensable gas source, means through which non-condensable gas is supplied to said space, means for conducting non-condensable gas to said vessel vapor space, electrically operated means for controlling the flow of non-condensable gas to the vessel, non-condensable gas withdrawing means in communication with the vapor containing portion of the vessel, other electrically operated controlling means for controlling the withdrawal of gas from the vessel, an electrical switch in circuit with the non-condensable gas withdrawal means and with said gas flow controlling means, temperature responsive means associated with the vessel and with said switch and adapted to actuate the switch and thereby control said electrically operated and said other electrically operated means to control the non-condensable gas withdrawal controlling means and the vapor flow controlling means, non-condensable gas cut-off means associated with the vessel space at a predetermined level therein and through which gas flows to said gas withdrawing means from said space, said cut-off device comprising a condenser for condensing condensable vapor, a condensate return conduit communicating with the condenser and the vessel vapor space, a second condensate return conduit communicating with said vapor space and the condensable vapor generating means, a pressure drop device in the path of flow of gas flowing from said space to the gas withdrawing means through said cut-off device, a second electrical switch in circuit with the non-condensable gas flow controlling means, and differential pressure responsive means in communication with the path of flow of said gas from the space to the gas withdrawing means through the cut-off device at opposite sides of the pressure drop device, said differential pressure responsive means being associated with the second electrical switch and adapted to break the circuit to the non-condensable gas flow controlling means upon an increase of pressure across the pressure drop device thereby to stop the flow of non-condensable gas to the vessel vapor space.

10. The combination of a vessel having a substance containing portion adapted to receive a substance to be heated, vapor receiving means in heat exchange relationship with substance in said substance containing portion, means for generating a condensable vapor heating medium, means through which the condensable vapor is supplied to the vapor receiving means, a non-condensable gas source, means through which non-condensable gas is supplied to the vapor receiving means, means for withdrawing non-condensables from said vapor receiving means, and means for regulating the amount of condensable vapor used in the vapor receiving means by controlling the amount of non-condensable gas sup-

plied to and withdrawn from said receiving means to thereby control the temperature to which the substance in the vessel is heated.

11. The combination of a vessel having a substance containing portion adapted to receive a substance to be heated, vapor receiving means in heat exchange relationship with substance in said substance containing portion, means for generating a condensable vapor heating medium, means through which the condensable vapor is supplied to the vapor receiving means, a non-condensable gas source, means through which non-condensable gas is supplied to the vapor receiving means, means for withdrawing non-condensables from said vapor receiving means, and means responsive to the temperature of the substance in the vessel for regulating the amount of condensable vapor used in the vapor receiving means by regulating the amount of non-condensable gas supplied to and withdrawn from the receiving means.

12. The combination of a vessel having a substance containing portion adapted to receive a substance to be heated, vapor receiving means in heat exchange relationship with substance in said substance containing portion, means for generating a condensable vapor heating medium, means through which the condensable vapor is supplied to the vapor receiving means, a non-condensable gas source, means through which non-condensable gas is supplied to the vapor receiving means, means for withdrawing non-condensables from said vapor receiving means, means for limiting the amount of non-condensable gas admitted to the vapor receiving means, means for withdrawing non-condensable gas from said receiving means, and means responsive to the temperature of the substance in the vessel for regulating the amount of condensable vapor used in the vapor receiving means by regulating the amount of non-condensable gas supplied to and withdrawn from said receiving means.

13. The combination of a vessel having a substance containing portion adapted to receive a substance to be heated, vapor receiving means in heat exchange relationship with substance in said substance containing portion, means for generating a condensable vapor heating medium, means through which the condensable vapor is supplied to the vapor receiving means, a non-condensable gas source, means through which non-condensable gas is supplied to the vapor receiving means, means for withdrawing non-condensables from said vapor receiving means, and means responsive to the temperature of the substance in the vessel for regulating the amount of condensable vapor used in the vapor receiving means by regulating the amount of non-condensable gas supplied to and withdrawn from said receiving means to maintain constant the temperature to which said substance is heated.

Certificate of Correction

Patent No. 2,432,985.

December 23, 1947.

DION K. DEAN

It is hereby certified that errors appear in the printed specification of the above numbered patent requiring correction as follows:

Column 6, line 39, for "thereo" read *thereto*; column 8, line 16, for "plate 88" read *plate 86*; column 9, line 2, for "coil 11" read *coil 111*; lines 35 and 48, for "packet" read *jacket*; column 13, line 21, for "supper" read *upper*; line 44, for "vapor" read *gas*;

and that the said Letters Patent should be read with these corrections therein that the same may conform to the record of the case in the Patent Office.

Signed and sealed this 14th day of December, A. D. 1948.
